[57] ABSTRACT

A sack-filling device is provided for filling particulate material into sacks having a sack valve without entrainment of air in the filled sack, permitting air within the sack to vent while preventing entry of outside air, comprising a sack-filling means, and a sealing insert having a wide end and a narrow end, adapted to sealingly engage the sack-filling means at the narrow end, and sealingly engage the inside of a sack valve at the wide end, to substantially close off the sack valve during filling of the sack.

FIG. 1

FIG. 2

FIG. 3

1
SACK-FILLING DEVICE

Pulverized materials, such as cement, plaster and hydrated lime, are mainly filled into valve sacks by semi-automatic filling machines. Hand-filling of sacks and the sewing of the sack openings after filling are not used any more, because of high labor costs. Instead, the sacks are designed with an opening provided with an internally-extending baffle or tube, referred to as a sack valve, adapted to receive the filling tube of an automatic filling machine. The filling machine normally includes a hopper adequate to retain a supply of the particulate material, and the material is fed from the hopper through the filling tube into the sack.

In the course of transport of the particulate material to the hopper, a considerable amount of air may be entrained with the material. In the case of cement, for example, the density of the material measured in the hopper of a filling machine is within the range from 1.1 to 1.3, while in a large silo or the like, after the material has been allowed to settle for a day or so, the density will have risen to from 1.3 to 1.5. This air is of course fed into the sack with the material, and must be vented from the sack, if possible, in order to obtain the rated weight of material in the filled sack.

One type of semiautomatic filling machine is known as a tube packer. In this apparatus, a rapidly rotating turbine wheel is used to transport the particulate material, such as cement, from the hopper through the filling tube into the sack. In this case, the sack opening is fastened around the tube. Due to the design of the tube, and the loose fit of the sack valve, air which enters the tube together with the particulate material can leave the sack through a channel formed under the tube, inasmuch as the outside diameter of the tube is smaller than the sack opening or the sack valve.

In filling sacks with this kind of device, the sack becomes taut as it is being filled, and increases in weight with the weight of the material, and the resulting change in internal volume of the sack causes air to be drawn into the sack during the first few seconds of the filling process. This air also must be removed from the sack at a later stage of the filling, to ensure that full weight of the sack is obtained, or alternatively a sack must be used that is of excessively large volume, to provide for both the given rated weight of particulate material and the air.

On some types of filling machines, the filling tube is fitted with an expandable collar, which opens out after the sack has been fitted to the tube, and before the particulate material begins to enter the sack. This collar helps to reduce the amount of air drawn in, but it cannot be designed to make a tight seal if the air that has entered with the material is to be allowed to escape from the sack towards the end of the filling process.

In accordance with the invention, a sack-filling device is provided for filling particulate material into sacks having a sack valve, without entrainment of air in the filled sack and which permits air within the sack to vent, while preventing entry of outside air. This sack-filling device comprises, in combination, a sack-filling means smaller in diameter than the inside diameter of the sack valve, and adapted to extend into the sack valve of the sack, to feed, particulate material thereto, and a sealing insert having a wide end and a narrow end, and to sealingly engage the inside of the sack valve at the wide end, substantially closing off the sack

valve, the insert being sufficiently resilient to flex away from the sack-filling tube and open the seal therewith for egress of gas such as air within the sack when under high gas pressure therewithin or under the stress applied to the insert by the sack under the weight of particulate material filled therein.

In a preferred embodiment of sealing insert, the insert is in the form of a truncated cone, mounted on the filling tube in a manner such that the narrow end of the cone points toward the inside of the sack, while the outer periphery of its wide end fits closely against the inner wall of the sack valve. The insert can however have any external configuration, as may be convenient to seal with the sack valve, such as elliptical, round, or polygonal (such as triangular, square, rectangular, and hexagonal), in a sloping or tapered form, straight or curved, convexly or concavely.

The sealing insert, such as the truncated cone, is made of a material that is sufficiently rigid to open out the sack valve when the sack is empty, and keep it open while sealingly engaging the interior walls thereof during the first stage of the filling process, so that ingress of air during this stage is prevented. However, the material, at least at the narrow end, should be sufficiently resilient so that it yields to the gas pressure that builds up in the sack toward the end of the filling process, and enables the gas such as air within the sack to escape past the insert. The insert should also be capable of yielding when the weight of the material in the sack is so great that the sack valve is forced by the load to assume a different shape. In either case, either the wide end, or the narrow end, or both, of the sealing insert become distorted, and break the sealing engagement with the sack valve and/or with the filling tube, allowing the gas such as air to pass the insert, and escape from the sack.

The sealing insert may be permanently attached to the filling tube, or it may be permanently attached to the sack valve. It may also be removably attached to either the filling tube or the sack valve, for easy replacement in case of damage or wear.

In the event that the sealing insert is in the form of a truncated conical or tapered tube, fitted in the sack, its larger diameter faces outward, so that the sack can be easily fitted over the insert and the filling tube of the filling machine. If the insert is fixedly attached to the walls of the sack valve, it is unattached at the end fitting over the filling means, and attached only at certain points to the sack valve walls, so that air will be able to escape therebetween during the later stages of the filling process. The part of the cone pointing toward the inside of the sack should be of such an inside diameter that it fits snugly and sealingly about the filling tube of the filling machine, but it should not be attached to the sack valve at any point at that end, since it must be capable of movement to accommodate the filling tube without rupturing the sack.

The sealing insert can be made of any material, such as a metal or a plastic, but it should be sufficiently resilient in the thickness used to become distorted under the described stress, but return to its original configuration when the stress is relieved. Suitable materials include stainless steel, polyethylene, polypropylene, polyvinyl chloride, polyamide, natural rubber, and synthetic rubbers. If the sealing insert is to be a part of the sack, it can also be made of the same material as the sack, for example, plastic in the case of plastic film

sacks, or paper in the case of paper sacks, but it may also be made of any material that can be bonded or held in the sack, and is suitable for the purpose.

FIG. 1 is a view in longitudinal section of a filling tube, sack valve and sealing insert in accordance with the invention.

FIG. 2 is a cross-sectional view taken along the lines 2—2 of FIG. 1.

FIG. 3 is a view in longitudinal section of another embodiment of sack valve and sealing insert in accordance with the invention, provided with circumferential ridges to improve the seal against the wall of the sack valve.

The filling machine shown in FIGS. 1 and 2 is especially adapted for filling particulate material such as cement into valve sacks. The hopper 1 of the filling machine, within which the particulate material is contained, is provided at its lower end with a turbine wheel 2, which is rotatable and which feeds material from the hopper into the filling tube 3. The filling tube is of a narrow diameter, so as to extend through the sack valve 9 of a sack 4 to be filled with the particulate material in the hopper.

A sealing insert in the form of a truncated cone 5 is mounted in a press and sealing fit on the outside of filling tube 3. The narrow end 6 lies on a portion of lesser outside diameter 10 of the filling tube, tightly embracing this portion of the tube. The end face 11 of the insert 5 abuts and seals against a corresponding face 12 of a portion 13 of wider diameter, at the nozzle 14 end of the filling tube 3.

The wide end 7 of the conical insert 5 is slightly (0.1 mm) wider than the inside diameter of the inner wall 8 of the sack valve 9, and consequently fits snugly and sealingly against this wall. Thus, air cannot pass between the end 7 and the wall 8, nor can it pass between the tube 3 and the inside wall of the narrow end 6 of the conical insert 5.

The sealing insert is made of a hard but resilient material, such as rubber or polyethylene.

In operation, particulate material is fed from the hopper 1 by the turbine wheel 2 into and through the filling tube 3 into the open interior of the sack 4. Tight sealing between the wide end 7 of the insert 5 and the wall 8 of the sack valve 9 prevents air from being drawn into the sack, as the sack becomes taut with the weight of material during the initial stages of the filling process. As the sack fills with material, however, the weight of material draws the sides of the sack downwardly, and this eventually results in deformation of the wide end 7 of the cone 5, which opens a passage for air between the end 7 and the inside wall 8, and allows the air (now, under pressure) inside the sack to escape. Eventually the sack is filled, and the tube 3 and the sealing insert 5 can then be withdrawn, and the opening into the sack closed.

In order to allow air within the sack to escape more easily at the end of the filling operation, the sealing insert can be designed with the lower part softer than the upper part. This can be done, for example, by making the walls of the narrow end thinner, or by grinding grooves into the material at this end. If this is done, however, the grooves should be inserted on the exterior of the material, to keep the inside of the narrow end smooth enough to obtain good seal is obtained against

the tube 3. It is also important that the outside periphery of the wide end 7 of the cone be completely smooth, to obtain a good seal against the inner wall 8 of the sack valve 9. Thus, any grooving or reduction in thickness of the walls at this end should be on the inside.

In order to improve the seal against the wall 8 of the sack valve further, the sealing insert can be provided with circumferential ridges, so that a longitudinal cross-section would show one or more protuberances, as shown in FIG. 3. The sealing insert 15 of FIG. 3 is provided with three circumferential ridges 16, 17, 18 sealing against the wall 8 of the sack valve. Due to the difference in space between the conical insert 15 and the inner wall 8 of the sack valve, the ridges ensure a good seal against the inner wall 8.

Having regard to the foregoing disclosure, the following is claimed as the inventive and patentable embodiments thereof:

1. A sack-filling device for filling particulate material into sacks provided with a sack valve without entrainment of air in the filled sack, permitting air within the sack to vent while preventing entry of outside air during the filling operation, comprising, in combination, a sack-filling means smaller in external diameter than the inside diameter of the sack valve, defining an annular space between its outside wall and the inside wall of the sack valve, and adapted to extend into the sack valve to feed particulate material into the sack; and a sealing insert of resilient material in the form of a truncated cone attached to the sack-filling means; the sealing insert being provided with ridges running circumferentially about the insert, to improve sealing between the sealing insert and the inside wall of the sack valve, having a wide end and a narrow end and having axial apertures only at the wide and narrow ends, coaxially embracing the sack-filling means and disposed across the annular space between the sack valve and the sack-filling means, sealing engaging in a secured and closed

25 relationship the outside of the sack-filling means at the narrow end, and sealingly engaging in a flexible relationship the inside of the sack valve at the wide end, to substantially close off the annular space, the sack-filling means having a recessed portion on its exterior wall, and the sealing insert at its narrow end sealingly engaging the sack-filling means at the recess, the insert being sufficiently resilient to flex away automatically from the inside wall of the sack valve and open the seal therewith for egress of gas via the annular space from within the sack when under high gas pressure therewith, or under stress applied to the insert by the sack under the weight of particulate material filled therein.

35 2. A sack-filling device in accordance with claim 1, in which the sack-filling means is a tube.

3. A sack-filling device in accordance with claim 1, in which the resilient material is rubber.

4. A sack-filling device in accordance with claim 1, in which the sealing insert is attached to the sack-filling means at a narrow portion thereof, and is lodged in a recess therein to improve sealing therewith.

5. A sack-filling device in accordance with claim 4, in which the sealing insert surrounds and is sealingly attached to the sack-filling means.
